FANFOLD PAPER TAPE SUPPLY-TAKEUP STRUCTURE

Betty L. McClurg, Arcadia, and Michael W. Grey, Temple
City, Calif., assignors to Addmaster Corporation, San
Gabriel, Calif.

Filed Aug. 15, 1973, Ser. No. 388,382

Term of patent 14 years

Int. Cl. D14—02

U.S. Cl. D26—5 C

Fig. 1.

Fig. 2.

Fig. 3.

Fig. 4.

Fig. 5.

FIG. 1 is a top front perspective view of a fanfold paper tape supply-takeup structure, showing our new design;

FIG. 2 is a front elevational view thereof;

FIG. 3 is a rear elevational view thereof;

FIG. 4 is a top plan view thereof; and

FIG. 5 is a right side elevational view thereof, the left side being a mirror image of the right side.

I claim:

The ornamental design for a fanfold paper tape supply-takeup structure, substantially as shown.
